UNITED STATES PATENT OFFICE

GEORGE S. HILTZ, OF BROOKLYN, NEW YORK, AND WILLIAM F. PURCELL, OF HOBOKEN, NEW JERSEY, ASSIGNEES TO STOCK QUOTATION TELEGRAPH COMPANY, OF NEW YORK, N. Y., A CORPORATION OF NEW YORK

PRINTING TELEGRAPH

Application filed November 28, 1927. Serial No. 236,085.

This invention relates to an improvement in printing telegraphs and has for one of its objects, the provision of an improved apparatus which will work much more satisfactorily than heretofore.

In practice, a number of receiving machines are on the same line with a single transmitter, and as these receiving machines are at remote points with regard to the location of the transmitter, it is impossible for the operator of the transmitter to know whether the receiving machines are recording properly or not. In order, therefore, that the receiving machines may be brought in unison with the transmitting apparatus, means are provided by the present invention whereby all of the machines on the line will be brought to unison automatically with definite relation to the number of rotations of the shaft of the transmitting machine. In other words, the present invention provides an apparatus whereby the receiving machines will be brought to unison automatically at certain predetermined intervals, which intervals may be varied as desired, in the design of the machine, and are independent of the operator.

Inasmuch as the general construction and operation of printing telegraphs is well known to those skilled in this art, the same will not be gone into in great detail herein. It will be sufficient to state that the receiving or recording machines comprise essentially escapement mechanism, spring operated so far as the scape wheel is concerned, the pawl cooperating with the scape wheel being operated by escapement magnets so wound as to be operated by currents of opposite polarity, these magnets having a common armature which is connected in some manner to the escapement pawl. The change in polarity in the current fed to these magnets is effected by a polar relay which, in turn is controlled by brushes cooperating with the transmitter shaft, which it will be understood, is constantly rotated except at such times that an impress is to be made by the recording machine. In these recording machines, also, an impress magnet is provided in series with the escapement magnets, this impress magnet being operable only when a circuit controlling

the transmitter is closed, at which time the current fed to the impress magnet is no longer reversed in polarity. In other words, the impress magnet, while in series with the escapement magnets, is not operable so long as the polar relay which reverses the polarity of the current fed to the machine is operating. In such machines it is customary also to provide a magnetic clutch or some type of clutch whereby the transmitter shaft can be held stationary momentarily while an impression is being made at which time the polar relay is not operating and a current of one polarity only is being fed to the impress magnet.

In addition to all of the foregoing, the transmitting mechanism comprises a sunflower or stationary commutator provided with a trailer rotatable with the transmitter shaft, and operable when the transmitter is operated to close a circuit to the magnetic clutch to stop the transmitter and permit current of one polarity to pass through the impress magnet to effect operation of the same, and to make an impression corresponding to the key depressed or transmitter circuit closed.

In the present invention means have been provided synchronized with the transmitter to impress current of a relatively high amperage on the line to effect the operation of stop or unisoning mechanism. We have shown this unisoning mechanism operative upon each revolution of the trailer shaft of the transmitter, but it is to be understood this is only by way of illustration, and for clarity of description, inasmuch as obviously the unisoning intervals may be varied if desired with respect to the rotation of the transmitter shaft, the object being to provide some means synchronized with the transmitter for bringing the receiving machine or machines automatically into unison.

In the accompanying drawings,

Fig. 1 is a side elevation of a receiving machine embodying our invention;

Fig. 2 is a plan view of the escapement mechanism on the line 2—2 of Fig. 1;

Fig. 3 is a view of the unisoning mechanism of Fig. 1, showing the parts in slightly different position;

Fig. 4 is a view similar to Fig. 3, of a modification;

Fig. 5 is a plan view of the apparatus shown in Fig. 4;

Fig. 6 is a view similar to Fig. 5 but taken at right angles thereto; and

Fig. 7 is a wiring diagram.

Referring first of all to the embodiment of our invention as shown in Figs. 1, 2 and 3, 1 and 2 designate the escapement magnets provided with a common armature 3 caused to be vibrated due to changes in polarity of the current sent through these magnets, as will be described hereinafter. The armature 3 has attached to it an escapement pawl 4 adapted to cooperate with scape wheel 5, permitting of the same to be rotated in the direction of the arrow in Fig. 1, for example, under the action of a spring as is usual in this art. The scape wheel 5 is mounted on a shaft 6, to be referred to as the type shaft, the type wheels being shown in dotted lines in Fig. 2 and designated 7.

The movement of the escapement pawl 4 is controlled by two stops, one designated 8, the other 9. The stop 8 is mounted for movement in the frame 10 by which it is carried. The movement, so far as movement toward the escapement pawl is concerned, being controlled and limited by a nut 11 and lock nut 12. The outward movement of the stop 8 is controlled by a spring 13 anchored to the frame 10 at 14, the other end of the spring bearing constantly against the outer end of the stop 8. The tension of this spring is conveniently made adjustable by an adjustment screw 15. As will be explained hereinafter, the stop 8 at certain predetermined intervals is moved for the purpose of setting into operation, the unisoning mechanism.

This mechanism which is adapted to engage and cooperate with the stop 8 comprises a stop pin 16 carried by ratchet pawl 4, and extending parallel to the axis of the type shaft 6, and this pin is adapted to cooperate with a unison pin 17 secured directly to the type shaft to prevent for a time, rotation of the type shaft, when the receiving or recording machine is not in unison.

Referring now to the wiring diagram of Fig. 7, 18 designates the usual keyboard of a transmitting machine shown with two keys 19 and 20, it being understood, of course, that this board actually is provided with the usual keys. 21 designates the sunflower or stationary commutator of the transmitting apparatus, the trailer 22, which is of usual construction and which cooperates with the segments of the sunflower being mounted upon the rotary shaft 23 which is geared to the shaft 24 of the transmitter. The transmitter shaft 24 is provided with a magnetic clutch illustrated diagrammatically and designated 25. The shaft 23 is provided with

three brushes, one brush 26 making constant contact with the hub of the trailer 22, while the two brushes 27 are adapted to be bridged periodically by a bridging contact 28, carried by the shaft 23. We might say at this point that in the present arrangement, the contacts 27 are adapted to be bridged each time the shaft 23 makes a revolution, but the bridging of these contacts with reference to the revolutions of the shaft 23, may be varied as desired.

29 designates a polar relay cooperating with brushes 30, 31 and 32, operably connected to the transmitter shaft 24, whereby the current passing through the magnets of the system is reversed in polarity periodically for the purpose of effecting vibration of the armature 3 of the escapement mechanism to effect an intermittent release of the scape wheel 5. 33 designates the impress magnet while 34 designates a relay for closing the circuit of the magnetic clutch 25. 36 is resistance in series with the escapement magnets 1 and 2, and the impress magnet 30, except when the contacts 27 are bridged.

Upon operation of the transmitter, as by depression of the key 19, for example, it being understood, of course, that the shaft 24 of the transmitting apparatus is in motion and that the escapement magnets 1 and 2 are receiving current so that the scape wheel 5 is being intermittently rotated, and hence the type shaft 6, together with the type wheel 7, a circuit is closed to correspond to the key depressed, for the purpose of stopping the transmitter shaft 24 and causing the magnet 33 to make the necessary or desired imprint.

The circuit through the transmitter and the various magnets, etc., may be traced from the positive side of the line through conductor 35, ring 36, key 19, conductor 37, contact strip 38 of the sunflower, trailer 22, when it is in position, brush 26, conductor 39, to the magnets of the relay 34 to ground. The energization of the relay magnet 34 will effect operation of its armature 40 and a circuit is now made to the magnet 25 of the clutch; the current passing by way of conductor 41, armature 40, stationary contact 42, conductor 43, clutch magnet 25 to ground 44. The transmitter shaft 24 will now be held stationary, current of one polarity only will be impressed on the line, escapement magnets 1 and 2 will no longer vibrate the armature 3, and the impress magnet 33 will now operate to effect an impression by the type wheel 7.

Upon release of the key 19, the circuits herefore described as being closed, are again opened, the scape wheel 5 again starting into rotation. Each time, however, that the brushes or contacts 27 are bridged by the strip 28, carried by the trailer shaft 23, resistance 36, normally in series with the escapement magnets 1 and 2 and impress magnet 30, is shunted and with this resistance shunted, current of a high amperage and of one polar-

ity is impressed on the line and this increased amperage will effect an increased pull on the armature 3 of the escapement magnets, to the left as viewed in Fig. 1, forcing the stop 8 to the left against the tension of the spring 13, thereby permitting the stop pin 16 to move out of the path of the unison pin 17 carried by the type shaft 6. If the receiving machine is in unison with the transmitter, the brushes or contacts 27 will be bridged at the instant that the unison pin 17 is about to engage the stop pin 16, with the result that the unison pin 17 will not engage the stop pin 16 and the type wheel shaft 6 will continue to rotate. If the machine, however, should be out of unison with the transmitter at the instant the brushes or contacts 27 are bridged, the unison pin 17 will not be in position to engage the stop pin 16 and inasmuch as these brushes are bridged only momentarily, it will be obvious that the instant these brushes are no longer bridged, the stop 8 will return to its normal position under the action of its spring, and the stop pin 16 will engage the pin 17 to bring the type shaft to rest, and it will remain at rest until the trailer shaft 23 has made another revolution, at which time, of course, the receiving machine has been brought to unison.

This arrangement, therefore, provides unisoning mechanism synchronized with the transmitter for bringing the receiving machines into unison periodically at regular intervals which have been described and illustrated as once for every revolution of the trailer shaft 23. The operation is full automatic, requiring no attention on the part of the operator whatsoever, and is independent of the key or keys operated on the keyboard 18.

In the embodiment of our invention illustrated in Figs. 4, 5 and 6, we have modified somewhat the specific construction just described. In this embodiment of our invention, the escapement magnets 1 and 2, as before, are provided with an armature 3 to which is attached the escapement pawl 4, cooperating with scape wheel 5 mounted on type shaft 6. This shaft as before, has rigidly attached to it a unison pin 17. The stops 8 and 9 for the escapement pawl 4 in this instance are stationary. The pole pieces of the escapement magnet 2, as viewed in Fig. 4, are extended upwardly above the top of the magnet toward the escapement pawl 4, as indicated at 45, and above these pole pieces we provide a stop armature 46, pivoted at 47, this armature having a plate 48 secured to it provided with an upturned flange 49 on its upper face, i. e., on the face adjacent type shaft 6, the plate 48 and flange 49 being so proportioned and positioned as to lie in the path of the unison pin 17 when the machine is out of unison. The operation of this device is in principle, the same as that just described in connection with the embodiment of

our invention as illustrated in Figs. 1, 2 and 3, and hence will not be described in any great detail so far as tracing the electric circuits is concerned. When the brushes 27 are bridged by the contact 28, as already described, current of one polarity and increased amperage is fed to the escapement magnets 1 and 2, by reason of the shunting of resistance 32, to cause the armature 46 to be drawn downwardly, as viewed in Fig. 4, against the tension of the spring 50, so that the unisoning pin 17 will not engage the flange 49, should the machine be in unison. If, however, the receiving machine should be out of unison, the armature 46 will be in the position shown in Fig. 4 at the time of the arrival of the pin 17 to the position shown in the same figure, it being understood, as previously explained, that the pin 17 is fixed upon the shaft 6 with a definite relation to the time of bridging of the contacts 27. The engagement of the pin 17 with the flange 49 will stop the rotation of the type shaft and the same will remain stationary until the shaft 23 has brought the contact 28 into bridging position again with respect to the brushes or contacts 37, by which time, of course, the receiving machine will be in unison with the transmitter, and the type shaft will be allowed to resume rotation.

In both embodiments of our invention, therefore, we have provided means operating automatically for unisoning the receiving machines so that they will be brought into unison with the transmitter, our arrangement as illustrated and described, being such that the unisoning operation takes place once at every revolution of the trailer shaft 23 of the transmitter, although, as previously pointed out, the time intervals may be varied as desired, the desideratum being to provide unisoning mechanism automatically operable and synchronized with the transmitter.

It is to be understood that modifications may be made in the construction herein illustrated and described within the purview of our invention.

What we claim is:

1. Printing telegraphs comprising a receiving or recording machine, unisoning mechanism for unisoning the receiving machine, an electromagnet for operating said unisoning mechanism, resistance normally in the circuit of said magnet to render the same inoperative for unisoning, and means automatically operable for periodically cutting out said resistance to effect operation of said magnet for unisoning.

2. Printing telegraphs comprising a receiving or recording machine, unisoning mechanism therefor, an electromagnet, resistance normally in the circuit of said magnet, and switch mechanism operating intermittently at regular intervals for shunting said resistance to cause said electromagnet to operate the unisoning mechanism.

3. Printing telegraphs comprising a transmitter and a receiver, unisoning mechanism for the receiver, an electromagnet, resistance normally in the circuit of said electromagnet, and a switch operated by the transmitter automatically for shunting said resistance to cause the electromagnet to operate the unisoning mechanism.

4. Printing telegraphs comprising a recording or receiving machine, escapement mechanism therefor, comprising an escapement pawl, an electromagnet for operating said pawl, a stop pin carried by said pawl for arresting the movement of the escapement mechanism to unison the machine, resistance normally in the circuit of said magnet to render the same inoperative for unisoning, and means automatically operable for periodically cutting out said resistance to effect operation of said magnet for unisoning.

5. Printing telegraphs comprising a recording or receiving machine, escapement mechanism therefor comprising an escapement pawl, a stop pin carried by said pawl adapted to arrest the type shaft of the receiver to unison the machine, an electromagnet for vibrating said pawl, resistance normally in the circuit of said magnet to render the same inoperative and means operable to periodically cut out said resistance to effect an abnormal movement of said pawl and stop pin whereby the movement of the type shaft will only be arrested if the recording machine is not in unison.

6. A recording printing telegraph comprising a scape wheel, an escapement pawl controlling the movement thereof, a unisoning arm moving with said scape wheel, a stop pin carried by said pawl and adapted to be interposed in the path of said unisoning arm to stop the unisoning arm only when the recording machine is out of unison, said pin being out of the path of said arm at all times when the machine is in unison.

7. A recording printing telegraph comprising a scape wheel, an escapement pawl controlling the movement thereof, a stop pin carried by the pawl, a unisoning arm moving with the scape wheel, a movable stop for said pawl, said stop being moved periodically to non-stopping position to permit said pawl to have an increased travel to carry said stop pin out of the path of the unisoning arm when the machine is in unison, this movement being so controlled that the stop pin will be interposed in the path of the unisoning arm when the machine is out of unison.

This specification signed this 25th day of Nov., 1927.

GEORGE S. HILTZ.
